UNITED STATES PATENT OFFICE.

ANTHONY G. FRANKENHOFF, OF ATCHISON, KANSAS.

LAP-ROBE.

958,617.

Specification of Letters Patent. Patented May 17, 1910.

Application filed December 30, 1909. Serial No. 535,619.

To all whom it may concern:

Be it known that I, ANTHONY G. FRANKENHOFF, citizen of the United States, residing at Atchison, in the county of Atchison 5 and State of Kansas, have invented new and useful Improvements in Lap-Robes, of which the following is a specification.

My invention relates to lap robes; and it consists in the peculiar and advantageous 10 means, hereinafter described and claimed, for contributing to the warmth of the feet, for enabling the user to move either foot and actuate an automobile pedal without lessening the protection and comfort afforded 15 by the robe, for precluding the possibility of the lap robe being displaced and lost from a vehicle when in use, and for enabling the user to see his feet when desirable and to quickly and easily disengage the same from 20 the lap robe when necessity demands.

In the drawings, accompanying and forming part of this specification: Figure 1 is a broken rear or inside view of a lap robe equipped with my improvement. Fig. 2 25 is a vertical section taken in the plane indicated by the line 2—2 of Fig. 1. Fig. 3 is a longitudinal vertical section taken through one of the foot-receivers of the improvement. 30 Similar letters designate corresponding parts in all of the views of the drawings, referring to which:

A is a lap robe which in general may be of the ordinary type—*i. e.*, may be made in 35 any desired form, of any material compatible with the purpose.

B is a strap, preferably of leather, which is comprised in the preferred embodiment of my invention and is utilized in the attachment 40 of the remainder of the improvement to the inner side of the lap robe near the lower edge thereof. The said strap B is connected to the lap robe by stitches *a* and extends throughout the width of the 45 robe. On each of its end portions the strap is provided with three (more or less) spaced rings *b*, for a purpose hereinafter set forth.

In addition to the strap B bearing the 50 rings *b*, my improvement comprises foot-receivers *C* that are movable independently of the lap robe to a limited extent, and flexible connections *D* intermediate the foot-receivers and the lap robe; the said flexible connections being, by preference, leather straps *c* 55 which are adjustable as to length, are connected to rings or eyes *d* on the tops of the

foot-receivers, and are provided with snap-hooks *e*, designed to be detachably connected to the rings *b*. From this it follows that the foot-receivers *C* and their connections *D* may be readily disconnected from the lap robe when it is not desired to use the same; also, that the connections of the foot-receivers to the lap robe may be located at different distances apart as different conditions make necessary. 60

In the practical use of a lap robe equipped with my improvement, the lap robe is arranged in the usual manner, and the user places the forward portions of his feet in 70 the foot-receivers *C*. With this done, the feet of the user are kept warm and he is able to see his feet and move the same to advantage in manipulating pedals, and this without moving or disarranging the lap 75 robe or otherwise detracting from the protection which it affords. It will also be noted here that by reason of my improvement there is no liability of the feet of the user becoming entangled in the lap robe, but 80 on the other hand the user can in an emergency quickly free his feet by merely withdrawing the same from the foot-receivers; and it will be further noted that by keeping his feet in the foot-receivers, the user is enabled 85 to prevent the wind from displacing the lap robe and carrying the same out of the vehicle.

The foot-receivers *C* may be of any desired form and may be made of any suitable 90 material without involving departure from the scope of my claimed invention. I prefer, however, to shape the foot-receivers as shown in order to enable the same to comfortably and snugly receive the fore parts of 95 the feet, and I also prefer for each foot-receiver to comprise a sole portion *m*, a vamp portion *n*, and a lining *p* of lamb's wool or other heat-retaining material. The vamp portion *n* of each foot-receiver may be 100 made of leather or any other material or materials without affecting my invention. I prefer, however, to have each vamp portion comprise an inner layer *r*, of rubber, adapted to exclude moisture and retain heat, and an outer layer *s*, of astrakhan or equivalent material, adapted to retain heat; the rubber layer and astrakhan layer being suitably connected together and to the sole portion. 105

It will be gathered from the foregoing 110 that the improvement as illustrated and described is adapted to be attached to lap robes

that are at present in use as well as to new lap robes.

While I have shown and described one form of my invention, it is to be understood that I am not limited to the details or the form or relative arrangement of parts disclosed, but that modifications may be made therein without departing from the spirit thereof.

10 Having described my invention, what I claim and desire to secure by Letters-Patent, is:

1. The combination of a lap-robe, a foot-receiver that is movable as a whole to a limited extent independently of the lap robe, and a connection intermediate the lap robe and the foot-receiver.

2. The combination of a lap robe, foot-receivers that are movable as a whole to a limited extent independently of the lap robe, flexible connections on the foot-receivers, and means on the lap-robe at intervals in the width thereof, whereby said connections may be attached to the robe at different distances apart.

25 3. The combination of a lap robe, foot-receivers that are movable as a whole to a

limited extent independently of the lap robe, flexible connections on the foot-receivers, provided with snap-hooks, and rings on the lap-robe at intervals in the width thereof for the engagement of the said snap-hooks.

30 4. An attachment for lap robes, comprising a strap adapted to be fastened to a lap robe, a foot-receiver movable as a whole to a limited extent with respect to the strap, and a flexible connection intermediate the strap and the foot-receiver.

35 5. An attachment for lap robes, comprising a strap adapted to be fastened to a lap robe, and bearing spaced rings, foot-receivers movable as a whole to a limited extent with respect to the strap, and flexible connections on the foot-receivers having snap-hooks detachably connected to certain of the rings.

40 In testimony whereof I have hereunto set my hand in presence of two subscribing witnesses.

ANTHONY G. FRANKENHOFF.
